UNITED STATES PATENT OFFICE.

JOHN S. FRIDOLPH, OF NEW YORK, N. Y., AND JEAN B. A. DUCHESNEAU, OF LEOMINSTER, MASSACHUSETTS, ASSIGNEES TO DE-LITE-US SPRING CLASP CORPORATION, OF NEW YORK, N. Y., A CORPORATION OF NEW YORK.

DESIGN FOR A PIN WHEEL.

Application filed March 15, 1928. Serial No. 25,876. Term of patent 3½ years.

To all whom it may concern:

Be it known that we, JOHN S. FRIDOLPH and JEAN B. A. DUCHESNEAU, citizens of the United States, and residents of the city, county, and State of New York, and Leominster, in the county of Worcester and Commonwealth of Massachusetts, respectively, have invented a new, original, and ornamental Design for Pin Wheels, of which the following is a specification, reference being had to the accompanying drawing, forming a part hereof, in which—

Figure 1 is a perspective view of a pin wheel showing our new design.

Figure 2 is a plan view of the same.

Figure 3 is a side view of the same.

We claim:

The ornamental design for a pin wheel, as shown.

JOHN S. FRIDOLPH.
JEAN B. A. DUCHESNEAU.
